UNITED STATES PATENT OFFICE.

EDWARD A. HAMILTON, OF NEW BETHLEHEM, PENNSYLVANIA.

CAR-COUPING TOOL.

SPECIFICATION forming part of Letters Patent No. 323,672, dated August 4, 1885.

Application filed February 16, 1885. (No model.)

To all whom it may concern:

Be it known that I, EDWARD A. HAMILTON, of New Bethlehem, in the county of Clarion and State of Pennsylvania, have invented a new and Improved Coupling-Link Holder, of which the following is a full, clear, and exact description.

The object of my invention is to provide a simple, inexpensive, and efficient implement for holding up the free ends of car-coupling links, so that they can enter the opposing draw-heads in coupling cars and without requiring the train-men to stand between the cars and expose themselves to injury.

15 The invention consists in a coupling-link holder comprising a handle, a pair of arms held to a shank adapted to slide along the handle, and adapted to be set projected from the handle and with their outer ends separated, 20 together with a spring acting to draw the arms backward from between the draw-heads as they approach each other in coupling the cars.

The invention consists, also, in particular constructions and combinations of parts of the link-holder, all as hereinafter fully described and claimed.

Reference is to be had to the accompanying drawings, forming part of this specification, in which similar letters of reference indicate 30 corresponding parts in all the figures.

Figure 1 is a sectional plan view of my coupling-link holder, showing it applied to use. Fig. 2 is a sectional elevation of the implement, showing the link-holding arms held and locked in place within the tubular shaft or handle of the holder; and Fig. 3 is an enlarged back end view of the holder.

The letter A indicates the hollow or tubular shaft or handle of the link-holder, the forward end of which handle is shaped to form a shoulder, *a*, and also a nipple, *b*, through which the link-holding arms or prongs B C may slide freely. I prefer to make the arm B solid with the shank D, and to pivot the arm C at *c*, near its rear end, to the shank, so that when the arms B C are drawn out from the handle A the heel *c'* on the arm C may be set against the base of a slot, E, cut in the nipple *b* for holding both arms B C projected from the handle 45 and separated at their outer ends for a distance measuring about three-fourths the

length of an ordinary coupling-link, F, as indicated in Fig. 1.

Near the back end of the arm-shank D is fixed the collar G, which loosely fits the bore 55 of handle A and serves as a guide to the movement both ways of the shank D and its arms B C, and between the collar G and the shoulder *a* of handle A is placed loosely on the shank the spiral spring H, which tends to draw 60 the arms B C back into the handle A.

Behind the collar G is formed on the reduced back end, *d*, of the shank D the conical or arrow-headed catch I, behind the shoulder *i* of which the spring J, held to the cap or ferrule K, fixed to the back end of the handle A, is adapted to engage for locking the arms B C 65 within the handle A.

As shown, the spring J is fixed at one end to the cap K, and passes through a side slot, 70 *k*, in the cap, so that the end *k'* of the slot stops the spring in proper position for the shank-head I to push the spring back, so it may lock automatically behind the head; but the spring may of course be fastened directly 75 to the handle A, if desired.

The operation is as follows: The spring J will be pressed back to release the arrow-head I of shank D and allow the arms B C to be projected from the handle A and locked when 80 spread apart by the heel *c'*, acting in the slot E of handle A, as before explained. The arm C then will be held extended, with its outer end beneath the end of the link F, which is held by the coupling-pin L in one draw-head 85 M, and the other arm, B, will be placed behind the opposite end of the link, whereupon, by turning the handle A axially one-quarter around, more or less, the free end *f* of the link may be held up at proper height to enter the 90 opposing draw-head O of the car to be coupled on, and as the draw-heads approach each other they will press the arm C, to trip its heel *c'* from the slot E, and the spring H then will act instantly to draw the arms B C back into 95 the handle A, so as to prevent crushing of the arms between the contacting draw-heads, and the spring J will catch under the head I to lock the arms within the handle.

The link-holder with the arms drawn out 100 or extended will be about two feet long, so that the train-man may readily hold the link

up by it as the cars are coupled without requiring him to stand between the cars and expose himself to injury.

It is evident that both the arms B C may be pivoted to the end of the shank D, in which case the arm B would have a heel adapted to lock in a slot opposite the slot E, in which the heel c' of arm C is set, but the construction with arm B solid to the shank, as shown, is preferred, as the solid arm is stronger to lift the outer end of the link than would be a pivoted arm, as will readily be understood.

Having thus described my invention, what I claim as new, and desire to secure by Letters

15 Patent, is—

1. A coupling-link holder comprising a handle, a pair of arms held to a shank adapted to slide along the handle, and one or both of said arms having a heel or projection adapted to 20 be set against the handle to hold the arms withdrawn therefrom and separated at their outer ends, and a spring acting to draw the arms back from between the draw-heads as the cars are coupled, substantially as herein set 25 forth.

2. The combination, in a coupling-link holder, of the tubular handle A, a shank, D, guided therein and having attached arms B C, said arm C being pivoted at c to the shank, and having a heel, c', adapted to enter a slot, E, 30 in handle A, substantially as specified, and a spring, H, acting to draw the arms B C back into the handle A, substantially as herein set forth.

3. The combination, in a coupling-link holder, of the tubular handle A, a shank, D, guided therein and having attached arms B C, said arm C being pivoted to the shank at c and having a heel, c', adapted to enter a slot, E, in handle A, and the spring H, acting to 40 draw the arms B C into handle A, substantially as specified, of the arrow-head I on shank D, and the spring J, held to handle A or a cap thereon, substantially as herein set forth.

EDWARD A. HAMILTON.
